UNITED STATES PATENT OFFICE.

GOTTFRIED TRITTEN, OF DEANSBORO, NEW YORK.

COMBINATION MATCH BOX AND CIGARETTE IGNITER.

Application filed April 7, 1926. Serial No. 100,223.

The main object of this invention is to provide a container suitable for the storage of matches in which a mechanism is provided for releasing and lifting the cover of 5 said container upon pressure of a button.

Another object is to provide a container having several compartments therein, one for the storage of matches, another for housing a cover-lifting mechanism, and a 10 third chamber in which matches may be ignited and shielded during their burning so that a cigarette may be inserted into this chamber and ignited without danger of having a match extinguished.

15 The above and other objects will become apparent in the description below, in which characters of reference refer to like-named parts in the drawing.

20 Referring briefly to the drawing, Figure 1 is a perspective view, showing the match box and igniter with the cover in partly opened position.

25 Figure 2 is a longitudinal sectional elevational view thru the container, showing the housing broken away to illustrate the cover lifting mechanism.

30 Figure 3 is a cross sectional view taken on line 3—3 of Figure 2.

35 Figure 4 is an enlarged top plan view of the container, showing the various compartments in detail.

40 Referring in detail to the drawing, the numerals 10 and 11 indicate the side walls of a container. These walls are integral with a bottom 12, and at their end edges are joined to a rear wall 13 and a front wall 14. The rear wall 13 is provided with hinge sleeves 15 thru which pins pass by which 45 hinges 16 forming part of a cover 17 are attached. The bottom, front and rear, and side walls, form a container open at the top which is normally closed by the hinged cover 17, and within the container, a housing 18 is provided. This housing forms a 50 small enclosed chamber in which the mechanism for lifting the cover upon depression of a button 19 is housed. The mechanism consists of a rack bar 20 which is provided with a longitudinal slot 21. A pin 22 rigidly mounted on the front wall 14 of the container registers in said slot and forms a 55 guide for limiting the longitudinal movement of the rack bar. Said rack bar has a shank 23 which extends outwardly thru an opening in the walls 11 of the container and wound about said shank is a coil spring

24 which is shouldered between the surface of the sides 11 and the button 19 integral with the shank. A pinion 25 is rotatably mounted about the rack bar on a stud 26. 60 This pinion has an arm 27 extending radially therefrom and at its outer end has a right angled curved finger 28.

65 Adjacent the housing 18, a match compartment 29 is provided. Between this compartment and spaced apart from the rear walls 13 of the container, a separating wall 30 is constructed which forms an additional narrower compartment 31. Access is had to this compartment thru one side of the container by providing an opening 32 in the wall 11 so that the tips of cigarettes may be 70 inserted into said compartment 31. The surface of the separating wall in the compartment 31 has a plate member 33 provided 75 which has a rough scratching surface. The rear wall 13 of the container has a longitudinal slot 34 formed therein thru which the sulphured ends of matches are inserted to the position where they come into contact with the striking surface of the plate 80 33. An additional striking surface 35 is mounted on the outer surface of the front wall 14 of the container so that matches 85 may be ignited from the outside of the container as well as within it. The free edge of the cover has a flange 36 extending downwardly therefrom which is adapted to lap over the side of the front wall 14 of the container and a recess 36' formed in this 90 flange engages a rounded lug 37 and releasably locks the cover in closed position upon the container.

95 The matches are stored in the compartment 29 and the container is used for igniting matches and putting them to their use for igniting cigarettes in a concealed and closed position so that stormy weather will not interfere with the operation. When it is desired to ignite a match in a closed compartment, the match is extracted from the compartment 29 by depressing the button 19. 100 This moves the rack bar 20 longitudinally, which being in meshed engagement with the pin 25, rotates the latter and causes the arm 105 27 to swing upwardly, carrying the curved finger with it. The arm 27 and curved finger 28 contact with the lower surface of the cover 17 and lift the latter to the open position, as indicated in dotted lines in Figure 1. 110 The match may then be extracted, the pressure on the button 19 released, the spring

again extending the shank 23 to the position shown in Figure 2, thus rotating the pinion and arm 27 downwardly into the compartment 29, permitting the cover to be manually locked by engaging the lug 37. The container is then turned so that a match which was extracted may be inserted thru the slot 34 into the compartment 31, causing the match to contact with the striking surface of the plate 33, which ignites said match, and when a cigarette or the like is inserted thru the opening 32, said cigarette may be ignited in concealed position so that rain or storm may not hinder the operation.

I claim:

1. In a device of the class described, a container having a plurality of compartments therein, a cover hinged to said container, a housing forming one of said compartments, an arm having one end pivoted in said housing, means integral with said arm for rotating the latter, and reciprocal means for rotating said first-named means.
2. In a device of the class described, a container having a plurality of compartments therein, a cover hinged to said container, a housing forming one of said compartments, an arm having one end pivoted in said housing, a pinion rigid with said arm and rotatable therewith, and means engaging said pinion for rotating said arm.
3. In a device of the class described, a con-

tainer having a plurality of compartments therein, a cover hinged to said container, a housing forming one of said compartments, an arm having one end pivoted in said housing, a pinion rigid with said arm and rotatable therewith, a rack bar slidable in said housing engaging said pinion, one end of said rack bar extending exterior of the container, said rack bar when depressed being adapted to rotate said arm to lift said cover, and means for extending the projecting end of said rack bar for repetition of the operation.

4. In a device of the class described, a container having a plurality of compartments therein, a cover hinged to said container, a housing forming one of said compartments, an arm having one end pivoted in said housing, a pinion rigid with said arm and rotatable therewith, a rack bar slidable in said housing engaging said pinion, one end of said rack bar extending exterior of the container, said rack bar when depressed being adapted to rotate said arm to lift said cover, a shank forming said member extending outwardly from the rack bar, a button on said shank, and a spring on said shank between the container and the button for normally extending said rack bar to active position and lowering of said arm.

In testimony whereof I affix my signature.
GOTTFRIED TRITTEN.
